TO WESTINGHOUSE ELECTRIC AND MANUFACTURING COMPANY, A CORPORATION
OF PENNSYLVANIA.

HEATING UNIT.

Application filed September 9, 1927. Serial No. 218,405.

Our invention relates to electric heating units and more particularly to base plates therefor.

An object of our invention is to provide 5 a relatively simple, inexpensive and easily manufactured heating unit.

Another object of our invention is to provide a single-piece base plate embodying side supporting portions for a refractory resistor-10 supporting member, laterally extending end portions embodying, respectively, a handle portion and a terminal-assembly-locating means, together with a central depressed heat-shield portion.

15 In practicing our invention, we provide a unitary base plate made of punched and pressed sheet metal and embodying spaced side portions located in a central horizontal plane for directly supporting a refractory plate, laterally extending end portions, the intermediate parts of which are bowed upwardly, one end portion being provided with a handle and the other end portion being provided with slots for locating a terminal-pin-20 supporting plate, and a central depressed portion constituting a heat shield for the heating unit. The unitary base plate embodies also laterally extending integral supporting portions 25 for engaging suitable supporting members for the heating unit.

30 In the single sheet of drawings:

Figure 1 is a top plan view of a base plate embodying our invention with a refractory plate, shown in part only, located thereon.

35 Fig. 2 is a view, in end elevation, of a heating unit embodying our invention.

Fig. 3 is a fragmentary view, in elevation from the handle end of the heating unit, and

40 Fig. 4 is a view, in side elevation, of an assembled heating unit embodying our invention.

An electric heating unit 11 embodies one or more refractory plates 12, a base plate 45 13 and a terminal assembly member 14.

The refractory plate 12 is a substantially 50 standard article of manufacture and embodies a rectangular flat plate provided with a plurality of overhung grooves in its upper surface for receiving a helically wound resistor 15. As the plate itself constitutes no part of our invention, it is not deemed neces-

sary to illustrate and describe it in further detail.

Heretofore, relatively heavy cast-metal 55 frames have been used as the supporting members for one or more of the refractory plates 12, but a supporting base plate made of cast metal must be made relatively heavy in order to obtain sufficient strength with 60 the result that the frame will have a relatively large heat-storage capacity.

The supporting base plate, more particularly embodying our invention, is made of a single piece of relatively thin sheet metal, 65 preferably sheet steel, and embodies two parallel-extending side portions 16 and 17, each of which constitutes a relatively narrow ledge upon which the side portions of the refractory plates 12 may rest, to be supported 70 thereby. Integral laterally extending end portions 18 and 19 are provided, the end portions of which are located in substantially the same plane as are the side portions, while the intermediate portions 21 and 22 are located in a different plane above the plane 75 of the side and end portions.

The intermediate portion 21 is further provided with a depending outer flange 23 to constitute a handle by means of which the 80 heating unit may be moved into and out of its normal operative position relatively to a device, or appliance, to be heated thereby.

The intermediate portion 22 of the other end member 19 is located in substantially the 85 same upper plane as is the portion 21 and constitutes a terminal-pin-protecting member. The integral side walls connecting the end portions of the member 19 with the intermediate portion 22 are each provided with 90 slots 24 which extend laterally of the heating unit, substantially as shown in Fig. 1 of the drawings.

The member 13 embodies also a central depressed portion 25 constituting a heat shield 95 and located in a lower plane than that of the side portion 16. Openings 26 and 27 are provided in the sheet-metal plate incidental to the punching and shaping portion necessary to change a flat sheet-metal plate to the form shown in the drawing. The slots or openings 26 and 27 extend laterally of the member 13, and, therefore, parallel to the end portions 18 and 19. It is obvious that 100

the side walls of the upwardly bowed portions 21 and 22 must be of substantially the same length as are the side walls of the central portion 25 and the forming die, or dies, are so made that when the end portions are bent upwardly and the central portion is bent downwardly, this requirement of substantial equality in length of the side walls will be met. The depressed portion 25 is bowed downwardly toward the central point, in order that it shall not buckle during expansion or contraction of the member 18 incident to heating and cooling.

In order to provide inwardly extending lug portions, designated by 28 and 29, respectively, the side wall portions of the part 25 is punched out by suitable means to the shape shown more particularly in Fig. 1 of the drawings, the opening left thereby in the side walls being indicated by 31 in Fig. 4:

Suitable openings 33 and 34 are punched, or drilled, in each of the members 28 and 29 in order that suitable securing screws may extend through the refractory blocks 12 and these members to hold the blocks in proper operative positions on the base plate.

As shown more particularly in Fig. 1 of the drawings, elongated openings 35 are provided at each corner of the base plate to receive screws 36 extending through the refractory plate as well. The elongated form of the openings is made necessary by the fact that refractory plates are not exactly uniform but vary because of slightly changing conditions during their manufacture.

The side portions 16 and 17 have depending flange portions 37 which, in turn, are each provided with outwardly extending portions 38. The portions 38 are, in turn, provided with a relatively narrow depending flange portions 39 which are adapted to rest upon suitable supports, such as glides, provided in the oven of electric ranges. By providing the flange portions 39 with an elongated recess 41, illustrated more particularly in Fig. 4 of the drawings, there will be but four points of support for the assembled heating element when located in its proper operative position on the supporting glides. The portions 37 may be provided with elongated openings 42 therein in order to reduce the amount of heat which will traverse the portions 37 and the portions 38 and which might flow from there to the supporting means.

The terminal assembly 14 embodies a sheet-metal plate 43, of substantially L-shape, in lateral section, one leg of which is bolted against the under surface of the intermediate portion 22 by a plurality of short screws 44 and nuts 45. A plurality of terminal pins 46 are insulatedly mounted on the other leg of the member 43, in a manner well known in the art. As shown in the drawings, three such terminal pins are provided to which the ends of the resistor wire 15 are connected in order

that a three-heat operation may be effected by a suitable switch (not shown), in a manner well known in the art. The terminal pins 46 extend a suitable distance beyond the outer edge of the portion 22, in order that they may extend into cooperating socket members (not shown) which are connected to a suitable source of supply of electric energy.

The device embodying our invention thus provides a sheet-metal base plate having portions thereof located in three different parallel-extending planes, certain portions of the plate being bent upwardly and another portion of the plate being bent downwardly. The downwardly-bent central portion constitutes a heat shield to reduce the amount of heat which is radiated downwardly from the bottom of the refractory plates 12. The slots, or openings 24, provide a convenient means for receiving the end portions of the terminal-pin-supporting plate in order to hold it in proper alignment laterally and longitudinally of the heating unit.

The device embodying our invention thus provides a single-piece sheet-metal base plate for supporting one or more refractory plates of electric insulating material in which is mounted a resistor. A plate of this kind is relatively inexpensive and has a relatively small heat-storage capacity.

Various modifications may be made in the device embodying our invention without departing from the spirit and scope thereof and we desire, therefore, that only such limitations shall be placed thereon as are imposed by the prior art or are specifically set forth in the appended claims.

We claim as our invention:

1. An electric heating unit comprising a sheet-metal base plate bent to comprise two spaced side portions, an integral cross member at one end shaped to constitute a handle, an integral cross-member at the other end bent to channel-shape, slots in the side walls of said cross member of channel-shape, a terminal-supporting bar having its ends fitting into said slots, a resistor operatively supported by the two side portions only, and terminal pins in said terminal-supporting bar.

2. An electric heating unit comprising a refractory plate, a resistor supported thereby, and a base plate for supporting the refractory plates, said base plate comprising two parallel-extending side portions for directly operatively engaging the refractory plate, integral end portions bent upwardly from the plane of the side portions and embodying respectively a handle portion at one end and a terminal-pin-supporting and protecting portion at the other end, and an integral heat shield bent downwardly from the plane of the side portions.

3. An electric heating unit comprising a refractory plate, a resistor therein, and a

unitary sheet-metal base plate comprising two side portions directly supporting the refractory plate, two integral upwardly bowed end portions, one end portion having an integral depending flange to constitute a handle and the other end portion having slots in the side walls, and a central downwardly-bowed portion constituting a heat shield, and

a terminal-pin-supporting plate having its ends fitting into the slots in one end portion. ¹⁰

In testimony whereof, we have hereunto subscribed our names this 31st day of Aug. 1927.

ERNEST E. SUTHERLAND.
